UNITED STATES PATENT OFFICE.

CARL E. ANDERSON, OF MAYWOOD, ILLINOIS.

WINDOW-FRAME.

1,345,471.

Specification of Letters Patent.

Patented July 6, 1920.

Application filed May 23, 1918. Serial No. 236,090.

To all whom it may concern:

Be it known that I, CARL E. ANDERSON, a citizen of the United States, residing at Maywood, in the county of Cook and State 5 of Illinois, have invented new and useful Improvements in Window-Frames, of which the following is a full, clear, concise, and exact description, reference being had to the accompanying drawing, forming a part of 10 this specification.

This invention relates to window-frames, and, more particularly, to window-frames of the type in which the windows are lowered or dropped into chambers or pockets when 15 it is desired to open them.

One of the objects of this invention resides in the production of a window-frame of this type in which telescoping means are utilized to strengthen the window-frame, and where- 20 by its rigidity is substantially increased and rattling of the window and frame is sub-stantially eliminated. Another object re-sides in the production of an improved means for constructing window-frames of 25 this type, which construction results in a very efficiently-operating structure, and which at the same time is comparatively low in cost of construction and exceedingly neat in appearance. Other objects will be ap-30 parent from the following description and the appended claims.

Window-frames of the type in which the window is lowered or dropped into a chamber or pocket when it is desired to open the 35 window, are used for many different purposes. For the purpose of illustrating my invention but one of these many applications has been illustrated. In the specific embodiment of the invention illustrated 40 herein, the invention has been adapted to a window as utilized in the sides of automobile-bodies, and especially automobile-bodies of the limousine type. Obviously, however, the invention is not limited to this 45 specific embodiment, other applications thereof being included within the spirit and scope of the invention as set forth in the ap-pended claims.

In the accompanying drawings, which 50 illustrate the specific embodiment of the invention as applied to disappearing windows of automobile-bodies—

Figure 1 is a diagrammatic view of the 55 side of the automobile body, the windows having been lowered in the pockets or cham-

bers provided therefor, and in which the upper side portions of the body co-operating with the window to close it have been re-moved:

Fig. 2 is a diagrammatic view similar to 60 Fig. 1 showing a window incorporating this invention;

Fig. 3 is a transverse section on the plane represented by the lines 3—3 of Fig. 1;

Fig. 4 is a transverse section on the plane 65 represented by the lines 4—4 of Fig. 2;

Fig. 5 is a sectional view taken on the line 5—5 of Fig. 4 and showing in skeletonized form the operating structure of the window.

Fig. 6 is a section taken on the plane rep-70 resented by the line 6—6 of Fig. 3;

Fig. 7 is a section taken on the plane rep-rented by the line 7—7 of Fig. 3;

Fig. 8 is a detail of the operating means used to raise and lower the window and 75 frame;

Fig. 9 is a view in perspective of a portion of the upper telescoping framework of the window-frame; and

Fig. 10 is a view in perspective of the in-80 ner telescoping frame of the window-frame.

Referring to the drawings, it will be ob-served that the window proper 10 is in-85 closed in a frame comprising the two side members 11 and 12 and the bottom member 13. It will thus be observed that the win-dow is completely inclosed in this frame on its two side and bottom edges, the top 90 edge being free from any covering what-so-ever, obviously, if desired, the top edge of the window could likewise be covered.

This frame is composed of any suitable material, preferably sheet-metal being sur-rounded by any suitable type of compressible 95 material, preferably felt, the compressible felt on these side members 11 and 12 snugly fitting and riding in the channels 14 and 15 of a secondary or outer frame. These chan-nels 14 and 15 are also preferably con-100 structed of sheet-metal and may be either individual pieces, one on either side of the window-frame, fitting in grooves such as 16 provided therein, and as such entirely sepa-rated from one another, or they may be united and interconnected by a strip, such 105 as 17, in which case the outer frame is con-nected in a manner the same as the inner frame, in which the window proper 10 is fastened.

As clearly indicated in Fig. 10, the lower 110

portion of the window-frame 13 has secured thereto a projecting lug 18, one of said lugs being located at either end of the lower section 13 of said window-frame (see Figs. 5 and 10).

The side upright members 14 and 15 of the outer section of the window-frame are equipped, in a position substantially in the middle of their length, with projecting lugs 10 20. The window-frame, consisting of the sides 11 and 12 and the base 13 in which the window proper 10 is positioned, as has been hereinbefore described, is snugly fitted in the channels 14 and 15 of the sides of the outer frame, and is adapted to be raised and lowered in the channels of the outer frame. In the upward movement of the window proper and its associated frame, the projecting lugs 18 on the lower member 13 of the frame 20 thereof, ride in the path of the projecting lugs 20 on the members 14 and 15 of the outer frame. It will therefore be evident that when the window proper and its associate frame is raised to a position where the 25 projecting lugs 18 come in contact with the lugs 20 of the other frame, any further movement of the window proper will carry with it not only its immediate frame consisting of the side members 11 and 12, but also the side members of the secondary frame 14 and 15 and its associated appurtenances.

The window proper 10 and its associated primary frame, consisting of the sides 11 and 12 and the bottom 13, and the secondary frame consisting of the sides 14 and 15 and the interconnecting link 17, are fitted in the chamber or pocket 21 of the door of the automobile, in such a manner as to provide, 40 a sliding connection between the secondary frame and the walls of this chamber. It consequently follows that when the window proper 10 and its associated frame are raised, the side members 11 and 12 will 45 slide in the channels 14 and 15 of the secondary frame, the secondary frame remaining stationary during this initial movement. However, when the parts of the frame have been raised to a position where the projecting lugs 18 on the lower portion 13 thereof contact with the projecting lugs 20 on the side channels 14 and 15 of the secondary frame, the secondary frame will move with the primary frame and the entire structure 50 will slide in the grooves 16 provided therefor in the chamber 21, the outer surface of the channels 14 and 15 sliding on the surface of the groove 16.

To reduce the friction between the channels 14 and 15 and the side walls of the grooves 16 in which they slide, a plurality of rollers, such as 22, 23, 24, and 25 is inserted in each one of these grooves 16. These rollers are so positioned that their 55 outer periphery projects a slight distance

beyond the bottom surface of the slot 16, and, consequently, the channels 14 and 15 in their upward movement slide along on these rollers. This very materially decreases the energy and effort required to 70 raise the window-frame, the frictional resistance offered to the raising of the frame being very materially decreased by this rolling contact.

Obviously, therefore, when the window 10 75 has been raised to its extreme upper limit, the primary frame will have been raised so that it is substantially entirely out of the pocket or chamber 21; whereas the secondary frame, which does not start to move 80 until the primary window is substantially half way out of said pocket, will have been raised to a position in which one-half of its length projects beyond the pocket and the other half is still inclosed within said 85 pocket. Said secondary frame therefore acts as a stiffening means for said primary frame and window when the said window has been completely raised out of said pocket. Said window is consequently 90 securely and rigidly held in all of its positions.

Obviously, any suitable means may be used for raising and lowering the window, and, for the purpose of illustrating this 95 invention, one of the well-known mechanisms used in raising and lowering windows in automobiles of the limousine type has been illustrated. As shown, this mechanism consists of the large sprocket-wheel 100 30 rotatably secured at 31 to the upright 32, and of a second and smaller sprocket-wheel 33 rotatably secured at 34 to the cross-piece 35. A handle 36 is secured to the axis of the sprocket-wheel 33. Connecting 105 the sprocket-wheels 30 and 33 is a chain 37. Secured to one of the links of the chain 37 is a projecting lug 38, which carries a pin 39 slidably fitted in the slot 40 of a plate 41 secured to the lower frame member 13 of the primary window-frame. The operating mechanism is contained within 110 the chamber 21 and is obscured from view by an outer casing 42 and by an inner lining (not shown) through which the operating handle 36 protrudes. 115

It will be evident from the foregoing description that, when the window is in its lowest position, the turning of the handle 36 will rotate both the sprocket-wheels and 120 will advance the chain 37 which in turn, through the medium of the pin 39, will raise the primary frame and window proper 10. As long as the chain 37 is advanced the primary frame and window 10 will continue to rise and when it has been advanced to a position in which substantially half of its length is outside of the chamber 21, the secondary frame, consisting of the channels 14 and 15, will be advanced with it. 130

This upward movement of the window will continue until it has reached the extreme upper position, at which time the pin 39 will drop into a pocket 42 formed in the 5 right-hand end of the slot 40, thereby locking the sprocket-wheel 38 against further movement.

When a window is supported, in accordance with this invention, with the collapsible or telescoping frames hereinbefore described, it is sufficiently rigid and strong so that it may be raised to any position outside of the receiving pocket 21, and maintained in all these positions without any 10 additional support.

Window-frames constructed in accordance with this invention and rigidly supported as hereinbefore described, may be very advantageously used in the construction of automobile bodies of the convertible type, the construction being especially beneficial for the window used in connection with the doors of the automobile-body. Thus, as 15 illustrated in Fig. 2, the door-window there shown is entirely supported by the telescoping or collapsible window-frame. As there illustrated, the opening for the door-window is provided with projecting flanges 43 and 44, in front of which the window is raised. 20 These projecting flanges may be equipped with any sort of compressible material, so that the union between the window and these flanges will result in an air-tight and water-proof joint. The outer portion of the window-frame is not inclosed in any manner whatsoever, and consequently the automobile-door 45 is absolutely independent of the upper side portions of the automobile-body and may be opened or closed with the 25 window in any position, the window being carried with the door rigidly held therein. With this construction it is therefore possible to rotate all the upper side portions of the automobile-body comprising the window 30 supporting posts into the roof of the car, and all the car-body windows can be lowered into pockets or chambers in the lower side portions of the automobile body when it is desired to convert a car-body of limousine 35 type into one of the open-body type. With this construction, the usual method of folding the door-window-frame downwardly on the inner side of the lower part of the door is obviated, and, consequently, with the window-frame construction of the type herein 40 illustrated and described, a much neater, more commercial, and efficient structure is obtainable.

Obviously, the invention is not limited to 45 the specific embodiment thereof herein illustrated and described, but is capable of many variations and applications without departing from its spirit and scope as set forth in the following claims.

Having thus described my invention, what

I claim as new and desire to secure by Letters Patent, is:—

1. A window frame structure comprising, in combination, a movable window-inclosing frame, a movable frame inclosing said window-frame, and means to move said first frame in said second frame to any one of a desired plurality of positions whereby the relative positions of the two frames with respect to each other will be changed for each 75 of said positions, said frames being maintained in any of the said positions to which they are moved.

2. A window frame structure comprising, in combination, a movable window-frame, a 80 movable window-inclosing frame, means to move said first frame in said second frame to any one of a desired plurality of positions whereby the relative positions of the two frames with respect to each other will be 85 changed for each of said positions, said frames being maintained in any of the said positions to which they are moved, and means for thereafter moving said first and second frames together as a unit to any one 90 of a desired plurality of positions, said unit being capable of being maintained in said positions.

3. In a device of the class described, in 95 combination, a window and window-frame-inclosing chamber, a primary window-frame, a secondary window-frame, means to raise said primary window-frame out of said chamber independently of said secondary frame to any one of a desired plurality of positions whereby the relative positions of the two frames with respect to each other will be changed for each of said 100 positions, said frames being maintained in any of the said positions to which they are moved, and means thereafter to raise said two frames together as a unit to any one of a desired plurality of positions, said unit being capable of being maintained in said 105 positions.

4. In a device of the character described, in combination, a window and window-frame-inclosing chamber, a primary window-frame, a secondary window-frame, means to raise said primary frame out of 110 said chamber for substantially one-half of its length, and means associated with said primary frame for thereafter raising said secondary frame with it for the remaining one-half of its length and to any intermediate positions, said frames being maintained in any of said positions to which they are moved.

5. In a device of the character described, in combination, a window and window-frame-inclosing chamber, a primary window-frame and a secondary window-frame of substantially the same length, means for raising the primary frame out of said chamber 115

120

125

- ber for substantially one-half of its length independently of said secondary frame, and means operable thereafter for raising said primary and secondary frames together for the remaining half of said length and to any intermediate positions, said frames being maintained in any of said positions to which they are moved, whereby said secondary frame is raised out of said chamber for substantially one-half of its length and being capable of being raised out of said chamber to any one of a plurality of positions, the said frames being maintained in any of said positions as which they are moved.
15. 6. In a device of the character described, in combination, a window, a primary window-frame inclosing chamber, a primary window-frame, and a secondary window-frame in which said primary frame is telescoped, said frames being contained in said chamber.
7. In a device of the character described, in combination, a window and a window-frame inclosing chamber, a frame inclosing said window, a second frame in which said first frame is telescoped, compressible means interposed between said first and second frames, means to move said first frame out of said chamber independently of said second frame, and means operable thereafter for moving both of said frames together as a unit.
8. In a device of the character described, in combination, a window and a window-frame inclosing chamber, a primary window-frame, a secondary window-frame in which said primary window-frame is telescoped, said frames being contained in said chamber, and means for raising said primary frame and its associated window completely out of said chamber, said secondary frame being raised out of said chamber for half of its length during said movement, said secondary frame serving to rigidly hold said window and primary frame when it is thus completely raised out of said chamber, said frames also being adapted to be raised to any intermediate positions between the extreme positions and maintained in any such positions.
9. In a device of the character described, in combination, a window and a window-frame inclosing chamber, a primary window-frame and a secondary window-frame of substantially equal length inclosed in said chamber, means to raise said primary frame and its associated window out of said chamber, said primary frame sliding in said secondary frame in said movement, and means associated with said primary frame operable after it has been raised substantially half of its length, said frames also being adapted to be raised to any intermediate positions between the extreme positions and maintained in any such positions out of the chamber, for moving said secondary frame 65 with it for the other half of its length.
10. In a device of the character described, in combination, a window, a primary frame inclosing the bottom and sides of said window, a secondary frame consisting of two channels in which the side members of said primary frame are telescoped, compressible means interposed between the contacting surfaces of said frames, a chamber for inclosing said window and said frame, grooves 70 fitted in the sides of said chamber in which said secondary frame is adapted to slide, rollers fitted in said grooves on which said frames slide, means to raise said primary frame in said secondary frame, and means 75 operable thereafter to raise said primary and secondary frames together as a unit on the rollers in said grooves.
11. In a device of the character described, in combination, a window, a primary frame 80 inclosing said window, a secondary frame consisting of two channels of equal length and inclosing the side members of said primary frame, compressible means interposed between the contacting surfaces of 85 said frames, a chamber inclosing said window and frame, grooves in said chamber in which said secondary frame is adapted to ride, rollers fitted in said grooves on which said frames slide, means operable to raise 90 said primary frame in said secondary frame and out of said chamber, and means associated with said primary frame, after it has been raised for substantially one-half of its length out of said chamber, to raise said 95 primary and secondary frames together as a unit on the rollers in said grooves; said secondary frame rising out of said chamber for substantially one-half of its length when the window and the said primary frame have been raised for their complete 100 length out of said inclosure, said secondary frame serving as a stiffening support to rigidly support said primary frame and window when thus raised out of said inclosure.
12. In a device of the character described, in combination, a movable window-inclosing frame, a movable frame inclosing said window-frame, means to move said first frame in said second frame, projecting lugs associated with said first frame, projecting lugs associated with said second frame located in the path of movement of the projecting lugs of the first frame, and means operable to move said window-frame in said frame inclosing frame until the lugs of said window-frame contact with the lugs of said frame-inclosing frame, whereafter said two frames will move together as a unit.
13. In a device of the character described, 110 a window and a window-frame-inclosing chamber, means to raise said window out of said chamber, and means associated with said window inclosed within said chamber,

for rigidly holding this window when thus raised out of said chamber, said means and said window being adapted to be raised to a plurality of positions outside of said chamber and maintained in any such positions.

14. In a device of the character described, a window and a window inclosing chamber, means to raise said window out of said chamber, a window stiffening and reinforcing frame, and means to move said window in said frame to any one of a desired plurality of positions, said window being maintained in any of the said positions to which it is moved.

15. In a device of the character described, a window and a window-inclosing chamber, means to raise said window out of said chamber, a window stiffening and reinforcing frame, means to move said window in said frame, and means thereafter to move 20 said window and frame together as a unit to any one of a desired plurality of positions, said unit being capable of being maintained in said positions.

In witness whereof I have hereunto subscribed my name.

CARL E. ANDERSON.
